UNITED STATES PATENT OFFICE.

JOHN FORHAN, OF NEW YORK, N. Y.

WINDOW-SCREEN.

SPECIFICATION forming part of Letters Patent No. 247,246, dated September 20, 1881.

Application filed June 20, 1881. (No model.)

To all whom it may concern:

Be it known that I, JOHN FORHAN, of the city, county, and State of New York, have invented an Improved Screen for Windows, of which the following is a full, clear, and exact description, reference being had to the accompanying drawings, forming part of this specification.

My invention relates to a screen adapted to be placed in or fitted to a window-opening, to prevent the entrance through the window, when open, of gnats or other annoying insects; and it consists in a window-screen composed of the parts hereinafter particularly described, combined and arranged to operate as herein-after specified.

Figure 1 is a front elevation of a window-screen embodying my invention, and showing the same in position in a window-frame. Fig. 2 is a cross-section on the line *xx*, Fig. 1. Fig. 3 is an enlarged cross-section on line *yy* of Fig. 1; and Fig. 4 is a perspective view, in detail, of the elastic rubber band which I preferably employ to actuate one of the rollers of my improved device.

In carrying out my invention I employ two cylinders or rollers, A and B, which may be of wood or metal, and which are of suitable diameter and are each of a length sufficient to extend from one edge of the window or sash opening to the other, along one side thereof, as seen in Fig. 1; and I find it preferable to use as these rollers the ordinary wooden shade-rollers, such as are well known in the trade. To one of these rollers, and longitudinally thereof, I attach by means of tacks or otherwise one edge of the sheet or piece of gauze or netting C, and to the other roller I secure the opposite edge of said gauze or netting in a similar manner.

The gauze or netting C may be of woven wire or the ordinary mosquito-netting, and should be of an area sufficient to wholly cover the window or sash opening, as seen in Fig. 1, and its length from its junction with one roller to the other should be preferably somewhat greater than the distance between the opposite sides of the window-frame, to which the rollers are secured, as hereinafter specified, so that when the rollers are in position the netting or gauze must be rolled up more

or less on the rollers, in order to bring it taut across the said window-opening between the rollers.

The roller A is placed at one side of the window-opening, along the edge thereof and closely against the face of the window-frame D, and is held in position by means of the axial pins *a*, one of which enters a suitable opening or bearing in the window-seat or end of the window-frame, and the other has a bearing in an eye or staple, *a'*, which is driven into the side of the window-frame. This eye or staple *a'* may be fixed at a distance from the end of the roller greater than the depth to which the axial pin on the opposite end of the roller enters its socket or bearing, and thereby the roller be conveniently detachable from its position, as described, without disturbing the staple or eye *a'*. The other roller, B, is similarly placed and secured in position on the window-frame at the opposite side of the window or sash opening.

In order that the gauze or netting may be stretched and held taut across the window-opening, and its edges between the rollers be thus held in a right line against the edges of the sash and window-frame, I employ the following simple and inexpensive devices, namely: a pin, *a²*, driven into the exposed end of the roller to one side of the axis thereof, and extending from the end, so that it strikes against or engages the side of the eye or staple, which forms the bearing for the axial pin on that end of the roller. The axis at the exposed end of the opposite roller, B, is composed of two pins, *b b'*, set in the roller end, at opposite sides of the axial line, and over one of these pins, *b*, is looped an elastic rubber band, E, which is then carried double around the other pin, *b'*, and preferably thence back around the pin *b*, and then again around pin *b'*, to stretch the elastic band, and is then looped over a pin, *d*, fixed at a convenient point on the window-frame, as seen plainly in Fig. 3. By this arrangement the elastic band operates to exert a constant and continuous force on the roller B to rotate the same in its bearings, and to thus roll up the gauze C upon it, and consequently to draw the gauze taut across the window-opening, the roller A being held rigid, as described.

It is evident that I have described a window-screen which is thoroughly effective for the purpose for which it is designed, and at the same time easily and cheaply constructed, 5 readily put in place, does not need to be exactly fitted for each window to which it is applied, as it fits itself thereto, and which, when not in use, can be rolled up in small compass, and stored in a limited space.

- 10 ◦ What I claim as my invention, and desire to secure by Letters Patent, is—

As a new manufacture, a screen for windows composed of the rollers A and B, attached to the opposite edges of the gauze or netting 15 C, the roller A being provided with axial pins a, one having bearing in the end of the window-frame D and the other in eye or staple

a', fixed in the side of said frame, and having the stop-pin a², and the roller B, having axial pin a at one end, with bearing in end of window-frame, and the double axial pin b b' at the opposite end, with bearing in eye or staple a', together with the elastic band E, looped or coiled about said double pin and provided with holding-pin d, all constructed, combined, 20 and arranged to operate substantially as and for the purpose specified.

Witness my hand this 10th day of June, A. D. 1881.

JOHN FORHAN.
